UNITED STATES PATENT OFFICE.

SIDNEY V. STEWART, OF CORRY, PENNSYLVANIA, AND EDWARD TIMBS, OF LOS ANGELES, CALIFORNIA, ASSIGNEES OF ONE-HALF TO UNION TOOL COMPANY, OF TORRANCE, CALIFORNIA, A CORPORATION OF CALIFORNIA, AND ONE-HALF TO AJAX IRON WORKS, OF CORRY, PENNSYLVANIA, A CORPORATION OF PENNSYLVANIA.

CATHEAD ATTACHMENT FOR DRILLING ENGINES.

Application filed April 15, 1925. Serial No. 23,434.

To all whom it may concern:

Be it known that we, SIDNEY V. STEWART and EDWARD TIMBS, both citizens of the United States, residing at Corry, county of Erie, State of Pennsylvania, and at Los Angeles, county of Los Angeles, State of California, respectively, have invented a new and useful Cathead Attachment for Drilling Engines, of which the following is 10 a specification.

This invention relates to steam drilling engines such as are employed in assembling the necessary equipment preparatory to rigging up an oil well and derrick. In conducting this operation, it is necessary to move parts of this equipment around; these parts are often very heavy and this entails considerable labor and time. The general object of this invention is to provide an attachment for the regular type of twin cylinder engine which is generally employed for this purpose in oil fields, which attachment carries a "cat-head" or winding spool on which a cable can be carried to pull 15 heavy machine parts along on skids, or to assist in hoisting parts of the apparatus on the derrick. One of the objects of the invention is to provide a construction which will enable a slight change in the construction 20 of the engine to adapt it for our purposes.

Further objects of the invention will appear hereinafter.

The invention consists in the novel parts and combination of parts to be described hereinafter, all of which contribute to produce an efficient cat-head attachment for drilling engines.

A preferred embodiment of the invention 40 is described in the following specification, while the broad scope of the invention is pointed out in the appended claims.

In the drawings:

Fig. 1 is a plan of the crank shaft end 45 of a twin-cylinder drilling engine of the type referred to, parts of the engine and engine-bed being broken away.

Fig. 2 is an elevation of this end of the engine viewed from the left end of Fig. 1

and with the bed and parts of the engine 50 broken away.

Fig. 3 is a vertical section taken about on the line 3—3 of Fig. 2.

In practicing our invention, we provide the engine frame with an outboard pillow-block or pedestal bearing which is attached to the side of the engine frame, and this bearing is in alignment with the two regular bearings for the engine shaft. We also provide an engine shaft with an outboard 60 journal received in the outboard bearing, and with a neck projecting beyond the outboard bearing. On this neck, the winding spool or "cat-head" is secured. In addition to securing the pedestal bearing to the engine frame, we also support it on the engine bed and secure it to the engine bed by holding-down bolts. The pillow block is a separate and distinct part from the engine frame.

Referring to the drawing, this type of engine includes a frame 1 with two oppositely disposed aligning bearings 2.

The engines of this type are provided with two disc cranks such as the disc crank 3 shown at the right in Fig. 1, each crank carrying a connecting rod 4. Between the bearings eccentrics 5 are placed, and between the eccentrics a sprocket wheel 6 is provided on the shaft. In adapting this 80 engine to our purpose, we provide a crank 7^a on a shaft 7 which is received in the main bearings 2 in the usual way, but on the side of the engine where the cat-head attachment is to be placed, we provide the 85 shaft with a journal 8 in alignment with the axes of the bearings 2.

On the side of the frame 1 adjacent to this journal 8, and below the crank 7^a we provide a pad or seat 9 (see Fig. 3) and on 90 this pad we secure a pillow-block or pedestal bearing 10. The pedestal bearing is secured in place of bolts 11. The upper part of this pedestal bearing receives the journal 8 as indicated in Fig. 3. In order to insure 95 that the bore 10^a of the bearing which receives the journal 8 will align properly with the main bearings 2, we provide dowel pins

12 which project from the side of the pedestal bearing so as to make a machine fit in drilled openings 13 in the face of the pad.

5 Beyond the journal 8 the shaft 7 has an extension or neck 14 on which a cat-head 15 is secured. In the present instance this cat-head is secured on the shaft by the key 16.

10 In winding a cable around the cat-head, considerable strain is developed in a horizontal direction, and in order to meet this strain, we provide holding-down bolts 17 in the engine bed 18 which pass through 15 an outer flange 19 projecting from the pillow-block.

The under face 20 of the pillow-block is in line with the under face 21 of the engine frame, and both of these faces rest on the 20 upper face of the engine bed, the engine frame being secured to the bed by suitable holding-down bolts 22.

In connection with the securing of the pedestal bearing, it should be noted that 25 the means for securing it includes bolts extending in two different planes substantially at right angles to each other, and this results in producing a very secure fastening.

The crank 7^a which carries the connecting 30 rod 4 adjacent to the pillow block 10 is provided with the counter-balance 23.

What we claim is:—

1. In a "cat-head" attachment for a steam drilling engine, the combination of an engine frame having a pair of aligning bearings, a crank-shaft carried in the bearings, with a crank at the side of the frame, a pillow-block constituting a part distinct from the frame of the engine and bolted 35 to the side of the engine frame below said crank, said pillow-block having an outboard bearing aligning with the first named bear- 40

ings and receiving the end of said shaft adjacent the said crank, said shaft having a neck projecting beyond the outboard bearing, and a "cat-head" carried on the neck. 45

2. In a "cat-head" attachment for a steam drilling engine, the combination of an engine bed, an engine-frame bolted to the bed and having a pair of aligning bearings, a crank-shaft carried in the bearings, with a crank at the side of the frame, a pillow-block bolted to the engine bed, constituting a part distinct from the frame of the engine and bolted to the side of the engine-frame 50 below said crank, said pillow-block having an outboard bearing aligning with the first named bearings and receiving the end of said shaft adjacent the said crank, said shaft having a neck projecting beyond the outboard bearing, and a "cat-head" carried on the neck. 55

3. In a "cat-head" attachment for a steam drilling engine, the combination of an engine frame having a pair of aligning bearings 60 and having a pad formed on the outer side of the frame adjacent the bearings, a pillow-block constituting a part distinct from the frame of the engine bolted to the engine-frame at said pad, said pillow-block having 65 an outboard bearing, dowel pins carried by the pillow-block and received in the engine frame at said pad to align the outboard bearing with the first named bearings, an engine bed, bolts securing the engine frame and the pillow-block to the engine bed, a crank shaft rotatably mounted in the said 70 bearings and having a neck extending beyond the said outboard bearing, and a "cat-head" attached to said neck. 75

Signed at Torrance, Calif., this 3rd day of March 1925.

EDWARD TIMBS.
